UNITED STATES PATENT OFFICE

HELMUT JUNGHANS, OF SCHRAMBERG, GERMANY

LOCKING DEVICE FOR SHAFTS OF CLOCKWORKS

Application filed August 6, 1928, Serial No. 297,901, and in Germany April 19, 1928.

My invention pertains to locking devices for the shafts of clockworks and similar mechanisms and more particularly to an improved device for locking the gripping shaft 5 of a clockwork employed in cinematographic apparatus, and which shaft is adapted and arranged to accomplish connections or controlling operations periodically or in predetermined intervals. Shafts of this kind are provided, for certain known reasons, with centrifugal or fly-wheel masses and, if a shaft of 10 a clockwork, as above stated, shall be arrested and fixed each time exactly in the same position, it is not sufficient to let the shaft which 15 usually revolves with considerable speed and momentum, strike against a locking or arresting lever even with a certain advance, since particularly under the action of the centrifugal or fly-wheel body the shaft will fly 20 back for a certain amount in case of an abrupt stop which is highly objectionable.

The object of my invention is to remove this disadvantage and with this object in view I 25 so construct and arrange the locking or arresting lever that the same will be adapted to directly engage and arrest the centrifugal or fly-wheel mass or body. To this end I preferably shape the lever to form a pawl or 30 detent adapted to catch into a dwell provided in the centrifugal body whereby the shaft will be momentarily arrested and safely locked and at the same time prevented from flying back, since the centrifugal body, preferably of cylindrical shape, is rigidly connected or integral with the shaft.

Having thus set forth in general the principles upon which my invention depends and having shown in particular the improvements 40 effected over the prior art, I shall now particularly describe one simple embodiment thereof of which I have shown diagrammatically in the accompanying drawings for the purpose of more fully disclosing my invention; but it is to be understood that such diagram shows only one of the several possible embodiments of my invention which I have successfully used in practice and that I do not 45 limit myself thereto inasmuch as many modifications may be devised by those skilled in

the art without departing from the spirit and scope of my invention.

In the accompanying drawings forming a part of this specification and showing for purposes of exemplification only a preferred form and manner in which the invention may be performed and practised.

Figure 1 is a front view of the centrifugal body secured to the shaft which is broken away; Figure 2 is a side view thereof, and Figure 3 is a plan view thereof.

Before proceeding to describe the specific construction of the locking device I wish to have it understood that though the essential feature of my invention resides in the provision of a notch-shaped dwell in the peripheral face or an end face of a cylindrical centrifugal or fly-wheel body for the pawl-like detent to engage therein, still I prefer to combine such a notch or dwell with a helicoid guiding groove in the peripheral or end face of the centrifugal body for the detent to slide and gradually descend therein prior to its catching into the notch when the rotation of the shaft is to be stopped.

In the embodiment shown the centrifugal body *b* is of cylindrical shape and firmly connected with the shaft *a* in any suitable manner. The hook-shaped pawl *c* is pivotally attached to some stationary member (not shown) and adapted to co-operate with the body *b* for the purpose of locking the shaft *a*. To this end the body *b* is provided with a recess or notch shaped to conform to the shape of the hook or nose *d* of the pawl, and located at a point corresponding to the requirement of stopping the shaft.

In the sectional plane of the notch there is cut a peripheral recess or groove of helicoid configuration extending from the wall *g* of the notch for about a quarter of a circle with its bottom face coinciding with the peripheral surface of the body *b* at about a quadrant's distance remote from the wall *g*, as will be clearly seen in Figure 2.

When the pawl occupies the locking position illustrated in Figure 2 the nose *d* thereof lies in the notch between the two walls *g* and *h* thereof. The wall or shoulder *h* constitutes the face against which the nose *d* abuts for

locking the shaft revolving in the direction indicated by an arrow in Figure 2, while the wall or shoulder *g* of the notch will lock the shaft with regard to the opposite moving direction. Consequently the operation of the locking device is such that when the shaft rotates in the direction of the arrow the pawl will slide on the helicoid bottom of the recess *f* until it drops into the notch and at the same time strikes against the wall *h* thereof, so that the shaft will be locked and at the same time prevented from flying back due to the limiting resistance offered by the rear wall *g* of the notch.

18 I have described with great particularity of detail a certain specific embodiment of my invention only, but I aim in the appended claim to embrace all modifications falling fairly within the scope of my invention.

19 What I claim is:

20 A locking device for the shafts of clock-works or the like comprising a centrifugal body securely mounted on the shaft and having a notch therein formed with oppositely disposed flat walls of unequal depth, and a recess extending spirally and circumferentially from the peripheral face of the body to and into the notch, said recess having a lateral guide face formed in the body, the bottom 25 of the recess where it enters the notch being above the bottom of the notch; and a pawl having a hook at one end and adapted, when required to lock the shaft, to bear on said lateral guide face and slide in the recess into locking engagement with the notch, rotation of the body in either direction being prevented by the opposite walls of the notch.

In testimony whereof I affix my signature.
HELMUT JUNGHANS.
